UNITED STATES PATENT OFFICE.

HERVEY R. STILES, OF DAVENPORT, IOWA.

DISH-CLEANER.

SPECIFICATION forming part of Letters Patent No. 596,130, dated December 28, 1897.

Application filed September 21, 1895. Serial No. 563,233. (No model.)

To all whom it may concern:

Be it known that I, HERVEY R. STILES, residing at the city of Davenport, in the county of Scott and State of Iowa, have invented a new and useful Improvement in Machines for Washing Dishes, of which the following is a specification.

The object of my invention is to produce a dish-washer which will thoroughly cleanse the dishes not only with much expedition, but with such perfection in its operative work as to render it unnecessary to use any other appliances upon the same after their removal from such dish-washer.

15 My invention relates to machines for cleansing dishes; and it consists in a cylindrical receptacle having adjusted therein two baskets, preferably of like form and equal dimensions, each basket being of semicylindrical form and 20 having one side a plane surface, the central portion of which is formed with such a concavity that when the two planes of such baskets are adjusted together a longitudinal interior chamber is formed for the reciprocation 25 therein of a reciprocating wash-dasher, and in such other combinations and details hereinafter described and claimed.

Figure I shows the cylindrical receptacle having a section of its lid raised on hinges 30 and having the two baskets adjusted therein, including the wash-dasher in the interior chamber. Fig. II shows the basket B before being placed in the receptacle. Fig. III shows the wash-dasher.

35 In the drawings similar letters refer to similar parts in the several figures.

The cylindrical receptacle A is constructed of either metal, wood, or any suitable material and of any desired capacity and having 40 a lid a so adjusted thereto as to be susceptible of being easily placed thereon and removed therefrom, such lid being constructed in two parts secured together with hinges a², the lid being so perforated at its central point a³ 45 as to permit the vertical dash-rod a⁴ to pass through the same with ease; also having a faucet in its side near the bottom to permit the outflow of the water when desired.

The receptacle designed to contain the two 50 baskets by adjustment therein may be constructed in any other desirable form than cylindrical.

Each one of the two baskets B is constructed of wire in reticular form and of any desirable capacity and being preferably, with respect 55 of each to the other, of equal dimensions and is of semicylindrical form and has one side a plane surface, as shown at b, the vertical central portion of which is constructed with such a concavity, as shown at b², that when the plane 60 surfaces of such baskets meet by being placed together a longitudinal interior chamber is formed between such concaved surfaces, as shown at b³ in Fig. I, and is adapted for the movement therein of a reciprocating wash-dasher. 65

Each one of such baskets may be made of any suitable material and with interstices of any desirable form and is so made as to permit the easy flow of water through its sides, 70 including its plane and concaved portions, and to safely contain the dishes to be cleansed. Also, the external sides of such baskets other than its plane side are preferably so constructed as to conform to the general form of 75 the receptacle in which such baskets are adjusted.

The wash-dasher E (shown in Fig. III) consists of a circular disk and made of any suitable material and being of such dimensions 80 as fit easily in the chamber b³, and to permit a rapid vertical reciprocal motion therein a vertical rod a⁴ is securely attached to the upper central surface of such disk and passes vertically through the perforation a³ of the lid when 85 the same is put in the receptacle and thence vertically to a convenient distance.

The combination of the cylindrical receptacle A and the two baskets B, as shown in Fig. I, is formed by adjusting in such cylindrical 90 receptacle such two baskets with their plane and concaved surfaces in contact and together, and thereby forming the interior chamber b³ and in which is reciprocated the wash-dasher E. 95

Whenever desired the dash-rod may be connected with any suitable motive machinery for producing a rapid reciprocating motion of the dasher in the chamber b³. Such machinery is preferably attached to the upper surface of the lid. 100

When the dish-washer is ready for operative work, the dishes, so far as practicable, are set in the baskets in a sharply-inclined posi-

tion. The baskets and receptacle in which they are adjusted are filled with hot water, or with cold water when desired, to a suitable depth, the water at the same time filling the 5 interior chamber to the same depth. To the water is added a little cleansing-soap or like material. The lid is then adjusted to the receptacle, and the wash-dasher and dash-rod being adjusted to their place, as described, 10 the wash-dasher is then made to rapidly ply with a vertical reciprocating motion in the interior chamber and thereby causes the water to be violently dashed and forced upon and over the dishes, and when proper care is taken 15 the dishes will need no other appliances for their proper cleansing after removal from the baskets.

When the capacity of the baskets is large,

the movement of the wash-dasher is preferably made by machinery attached to the upper surface of the lid.

What I claim as my invention, and desire to secure by Letters Patent, is—

In a dish-washer, the combination of a receptacle, two semicylindrical reticulated dish-holding baskets placed therein, the meeting plane surfaces of each basket being formed with a longitudinal concavity whereby an interior chamber is formed, and a dasher adapted to reciprocate within said interior chamber, 25 30 substantially as described.

H. R. STILES.
